UNDERGARMENT

Sadie J. Woodruff, Asbury Park, N. J., assignor to
The H & W Company, Newark, N. J., a corpora-
tion of New Jersey

Application August 25, 1948; Serial No. 46,015

1 Claim. (Cl. 128—280)

1

This invention relates to undergarments for women, more particularly to a brassière.

One object of the invention is a new and improved garment of the character set forth that is particularly useful for wear by mothers.

Still another object is a brassière which is characterized by its simplicity in design, its easy and comfortable wear, and the economy with which it may be manufactured.

These and other objects will become more apparent in the following description and accompanying drawing forming part of this application.

In the drawings—

Fig. 1 is a perspective view of a garment embodying the invention;

Fig. 2 is a view of the inner side of the embodiment shown in Fig. 1;

Fig. 3 is a section along the lines 3—3 of Fig. 2; and

Figs. 4 and 5 are front and rear elevations of one portion of the garment shown in Figs. 1 and 2.

In one aspect the invention resides in a readily convertible brassière which may be worn by mothers when nursing with marked comfort and complete protection against leaky breasts and which may be readily adapted to comfortable wear when not nursing by a simple conversion change.

More particularly the undergarment in accordance with this invention embodies, among other new and improved features, an outer portion forming a complete brassière in itself for ordinary wear and including suitable breast pocket structures and inner readily removable breast protective portions fastened to strips forming parts of the lower reinforced border edge of the garment.

Referring to the figures, this new and improved garment is provided with two pockets 10—10 adapted to receive the breasts. The inner meeting edges of the pockets are joined by a zipper 14 extending downwardly to a point below or approximating the lower breast lines.

Each pocket 10 may be formed of a single piece of material and shaped in the desired manner by means of darts 16''. In the present embodiment three such darts are provided in each pocket.

The lower front portion of the garment comprises a narrow border edge part 12 and a part 10' intermediate the pockets 10 and border 12. In the particular embodiment shown the parts 10' are formed integrally with the pockets 10 and are fastened together along their meeting edges at 13 in line with the zipper 14. The border 12 tapers slightly in width from its center.

2

The side and back portions of the garment comprise corresponding panels or sections 16 and 18 the latter being fastened to the outer sides of the pockets 10, with the lefthand section 18 (Fig. 2) having a short strip of elastic or other similar material 20 having eyelets 22 thereon for engagement with corresponding hooks 24 on the righthand section 18. The sections 16 and 18 are connected to the pocket 10 by suitably lined 10 seams 16' to prevent raw edges of the material from chafing the wearer. The adjoining sections 16 and 18 on each side in the present embodiment are formed of a single piece of material with a pleat 18' in the center thereof. The upper and 15 lower edges 26 and 28 of the pockets 10 and their adjoining sections as well as the lower edge 30 of the front border strip are provided with any suitable finish. The side sections 16, 18 and the outer portions of pockets are formed so that the 20 upper edges thereof form a continuous line tapering gently and uniformly downward to form a narrow back part.

In addition to the elastic member 20 in the back of the garment, elastic triangular inserts 32 are provided at the ends of the front border strip 12 and form in effect part of the sections 16. These inserts 32 extend above the border 12 and are fastened to the front portions 10'. In this way additional flexibility is provided in line with 25 the border 12 and front portions 10'. The shoulder supports for the garment comprise a pair of adjustable straps 34 secured at one end to the peaks of the pockets 10 located approximately over the centerline of the breasts and at the other 30 end to the upper edge of the section 18. By adjusting these straps the desired support can 35 readily be attained.

The brassière is provided with inner readily removable breast covering portions 36 for protection against leaky breasts, these portions being of flannel or other suitable absorbent material. These protective portions 36 are fastened to and supported by an inner front strip 12' which is fastened to the inner side of border strip 12. It is wider than the border 12 and therefore extends up above the upper edge thereof, being fastened to the front portion 10' along the lines 50 and 51. The upper edge of the strip 12' is reinforced by a narrow strip 46 on its inner edge and male snap fasteners 48' are incorporated in this reinforced edge on its inner side. The protective portions 36 are provided with lower straight edges 38 which are reinforced by narrow strips 46 with female parts 55 48 of snap fasteners incorporated therein. The

edges 38 are insertable between the edges 52 of the strip 12' and the snap fasteners 48, 48' are fastened for assembly of the two portions of the garment for use by nursing mothers.

The protective portions 36 are provided with conventional darts 55 for the usual purpose, and are shaped in pocket form to conform to the breasts. The side of the protective portions 36 next to the pockets 10 may if desired be provided with a moisture proof or resistant covering 42.

The protective portions are thus fastened to and carried by the border strip 12' and are structurally independent of the pockets 10 but protect the garment against soiling or wetting from the breasts. With the protective elements detached and removed the garment may be worn by the mother with the same comfort as with conventional brassières.

It is to be noted also that with this new and improved construction for an undergarment the wearer can not only obtain adequate and secure support for the breasts, but can also readily and easily expose one or the other of them for nursing, changing dressings and the like. Moreover, with the use of the removable protective portions better and complete protection is obtained and they can easily be changed without changing the garment. They are also securely held in position in the garment and will not slip or get out of position even when the garment is opened. With this construction the protective portions can be securely fastened in place without danger of displacement while being worn. Moreover, by reason of the particular structure, the fastening

means is completely covered to protect the wearer and comfortably support the breasts. The protective pockets 36 are provided with straps 44 for the purpose of adding additional absorptive pads of gauze or sterile dressing, readily removable for renewal.

What I claim is:

A brassière wearable interchangeably by nursing mothers and women generally comprising breast supporting parts with means for readily opening and closing the breast supporting parts, said brassière comprising a narrow front reinforcing band at the bottom of the breast supporting parts having an inner part whose upper edge is unattached to the adjacent part, said inner part having readily detachable fastening means along its upper edge for readily receiving in a detachable manner protective inner pockets extending upwardly to points adjacent the upper portions of the breast supporting parts, and protective pockets secured to the brassière only along said narrow reinforcing band.
